UNITED STATES PATENT OFFICE.

EDWARD R. HIBBARD, OF CHICAGO, ILLINOIS.

LANTERN.

1,156,229.

Specification of Letters Patent.

Patented Oct. 12, 1915.

Application filed November 10, 1913. Serial No. 800,064.

To all whom it may concern:

Be it known that I, EDWARD R. HIBBARD, a citizen of the United States, residing at Chicago, in the county of Cook and State of Illinois, have invented a certain new and useful Improvement in Lanterns, of which the following is a full, clear, concise, and exact description, reference being had to the accompanying drawings, forming a part 10 of this specification.

My invention relates to lanterns.

Prominent objects of the invention are to provide a simple, practical and efficient device of the kind mentioned; to arrange for 15 the changing of the color of the lamp or lantern at will; to permit this change of color to be accomplished instantaneously and easily; to provide a practical and effective construction for accomplishing this result; and 20 to secure the foregoing and other desirable results in a simple and expeditious manner.

In carrying out the invention in the way herein set forth I provide a lantern or lamp either electric or oil with one or more suitable diaphanous members together with 25 suitable mechanism or instrumentalities by which said member or members may be shifted or manipulated so as to cause the lamp or lantern to give any one of several 30 colors as desired. I show several views of the construction by which this result may be accomplished, illustrating ways in which my invention may be applied or carried out. It will be understood that other types of 35 construction may be employed without departing from the spirit of the invention.

In the accompanying drawings Figure 1 is an elevation of a lantern embodying my invention; Fig. 2 is a vertical longitudinal 40 section of the same; Fig. 3 is a sectional view taken on line 3—3 in Fig. 2; Fig. 4 is a horizontal cross section taken on line 4—4 in Fig. 2.

Referring to Figs. 1 to 4 inclusive, I show 45 a lantern of more or less conventional shape and size conveniently constructed with a body portion 1, a top 2 with intervening wire members 3 between the top and bottom 1 and 2 and having a handle 4 pivotally connected with the top 2. An electric lamp 6 is shown mounted upon the bottom 1 and as a convenient arrangement for supplying current for said lamp 6 a battery 7 which may be any suitable or preferred type of 50 dry or other battery, is mounted within the bottom 1 which to accommodate the same

is preferably made in the form of a hollow shell or case having a threaded connection with a top or cover portion 1^a, upon which latter the lamp 6 is mounted. A series of 60 diaphanous members 8, 9 and 10 are provided, the same being of different colors, as for example the member 8 is blue, the member 9 is green, and the member 10 is red. These members are preferably cylindrical 65 in form and of different size or diameter so that they may be arranged telescopically or nested within one another for purposes as will hereinafter appear, and said members are arranged for vertical movement into position surrounding the lamp 6 in which position the member 8 is shown, and also into the elevated position above said lamp 6, and within the top 2, which is preferably made in the form of a hood or cover as best shown in Fig. 2. Thus when any one of the members 8, 9 and 10 is in a lowered position, as for example the member 8, the lamp or lantern will give out a light colored by said member, in this case a blue light. When, however, said member 8 is elevated and one of the other members 9 or 10 is lowered, instead of a blue light, a light colored by one of the other members will be given, as for example a green or red light. As a simple 80 and ready means of manipulating these members 8, 9 and 10 to give different colored lights, said members are provided with handles 11, 12 and 13, respectively, which handles extend up through the top of the hood 70 75 85 90 95 100 105 110

2 so as to be accessible as for example at 14 above the hood 2 to permit ready raising and lowering of the vertically shiftable diaphanous members 8, 9, and 10. Thus the lantern may be caused to give out any desired color of light and a change quickly made to any other desired color. The intermediate wire members 3—3 are of any preferred shape or construction, so as to protect the members 8, 9 and 10 which would ordinarily be made of glass but might of course be made of other proper material. Suitable guide wires 15, 16 and 17 are interposed between the members 8, 9 and 10, and within the latter to properly guide said members in their upward and downward movements.

The handles or rods 11, 12 and 13 are provided with longitudinal slots 11^a, 12^a, and 13^a, adapted to receive a wire or rod member 2^c on the top of the hood 2 and having lateral recesses whereby when said handles 11,

12 and 13 or any of them are elevated they may be tipped to one side as shown in Fig. 3, so that the lateral ends of the slots 11^a, 12^a and 13^a may engage the wire 2^c and lock said handles in elevated position.

It will be understood that although electric lamps are herein shown the invention is equally applicable to lanterns, lamps and other devices having oil or other lighting 10 instrumentalities, and is also applicable to other forms of electric lamps or lanterns.

It is understood that changes and modifications can be made without departing from the spirit of the invention.

15 What I claim is:

1. A device of the class described comprising a lighting element, a diaphanous tubular movable member, an outer casing inclosing said tubular member and having 20 an opening substantially in register with said lighting element, a member secured to said movable member for moving said member toward and away from said lighting element and being of a length substantially 25 equal to the distance which the tubular member is adapted to be moved, said member being provided with a slot having an offset therein a member extending into the slot and forming a means for securing said tubular member against movement with relation 30 to said outer casing when in engagement with the offset in the slot.

2. A device of the class described com-

prising a lighting element, a plurality of diaphanous movable members, an outer casing inclosing said members and having an opening substantially in register with said lighting element, members secured to each of the diaphanous movable members and extending through the casing in different 40 planes, a member mounted on the casing and extending into the path of all of said members, said member coöperating with the members which are attached to the movable tubular members and forming a means for 45 supporting the tubular members in one position.

3. A device of the class described comprising a lighting element, a plurality of diaphanous movable members, an outer casing inclosing said members and having an opening substantially in register with said lighting element, a member extending from each of said movable members and through 50 a slot in the casing, a member extending across each of said slots, and engageable with one or more of the members which extend from the diaphanous movable members, to hold said members within the casing.

In witness whereof, I hereunto subscribe 60 my name this 7th day of November, A. D., 1913.

EDWARD R. HIBBARD.
